APPARATUS FOR THE DESTRUCTIVE DISTILLATION OF SOLID BITUMINOUS MATERIALS

Filed Dec. 21, 1921

Fig. 1

UNITED STATES PATENT OFFICE.

ARTHUR M. SMITH, OF CLEVELAND HEIGHTS, OHIO.

APPARATUS FOR THE DESTRUCTIVE DISTILLATION OF SOLID BITUMINOUS MATERIALS.

Application filed December 21, 1922. Serial No. 608,168.

This invention relates to improvements in apparatus for the destructive distillation of solid bituminous materials such, for instance, as bituminous and lignite coals, peat and shales, to produce illuminants, water-gas, coke, tars, etc.

One object of this invention is to produce apparatus of the character indicated whereby the destructive distillation of solid bituminous materials may be effected more efficiently and more economically and with greater facility than heretofore.

Another object is to produce apparatus of the character indicated whereby the destructive distillation of solid bituminous material may be attained in such a manner as to effect the production, from said material, of water-gas or illuminating gas, as the case may be, in greater quantity per measure of a given material being treated, and of higher quality, than heretofore, and to produce coke of a high B. t. u. value and of a quality suitable for the finest metallurgical processes.

With these objects in view, and to attain other objects hereinafter appearing, this invention consists in certain meritorious features of construction, and combinations and relative arrangements of parts, hereinafter described in this specification, pointed out in the claims, and illustrated in the accompanying drawings.

In said drawings, Figure 1 is an elevation, largely in section and partly diagrammatic, of said apparatus. Fig. 2 is a vertical section taken along the line 2—2 in Fig. 1, looking in the direction indicated by the arrow. Fig. 3 is a horizontal section taken along the line 3—3 in Fig. 1, looking downwardly.

To most successfully attain the hereinbefore mentioned objects of my invention my improved apparatus for the destructive distillation of solid bituminous material preferably comprises a retort having a treating chamber in which a body of said material is to be confined, a condenser, a pipe discharging at one end portion thereof into the condenser and communicating at its other end portion with the aforesaid chamber and arranged to conduct vapors and gases to the condenser from one end portion of said chamber and also arranged externally of said chamber and condenser between said end portions of the pipe, a condensate-receiving chamber arranged to receive condens-

ate and accompanying uncondensed gases from the condenser, a passageway communicating with and at the upper portion of said condensate-receiving chamber and extending to and around and endwise of the aforesaid pipe, means whereby gases may be washed in said passageway between said pipe and the condensate-receiving chamber, a passageway discharging at the opposite end portion of and into the aforesaid treating chamber, means whereby gases conducted by the last-mentioned passageway may be heated to produce a gaseous heating agent, and means whereby gases may be forced into said last-mentioned passageway from the passageway first mentioned in this paragraph.

In the hereinbefore mentioned drawings, 6 indicates a closed treating chamber formed interiorly of a substantially vertical retort which is preferably annular in cross-section, and 7 indicates the surrounding wall of said chamber, and said wall is composed of a highly refractory material such, for instance, as carborundum and surrounded by a steel shell 8. The top wall and bottom of said chamber are respectively formed by doors 9 and 10 constructed and applied in any approved manner. Said doors are shown in their closed position, and eye-bolts 12 and thumb-nuts 13 are employed for securing said doors in said position. Each bolt 12 has its eye pivotally connected, as at 15, to the shell 8, and has its shank extending, in the operative position of the bolt, through a slot 16 in the adjacent door and beyond the outer side of said door, and the nut 13 associated with said bolt is threaded onto said shank and adapted to cooperate with said bolt in locking said door in its closed position, and obviously loosening of said nut in relation to said door renders said bolt free to be swung outwardly from the door to permit opening of the door. The top door 9 is vertically pivoted, as at 17, to the surrounding wall of the chamber 6, and the bottom door 10 is pivoted horizontally, as at 18, to the shell 8. The bottom door 10 is closed, if not already closed, and secured in its closed position, preparatory to charging the chamber 6 with material to be treated in said chamber, and the top door 9 is opened, if not already open, preparatory to and to permit the feeding of said material into said chamber at the upper end of the chamber, and closed and secured in its closed position 110

upon supplying said material to said chamber, and when said material has been supplied to said chamber the doors 9 and 10 are sealed in any approved manner to render the 5 joints between the surrounding wall of said chamber and said doors fluid-tight.

By the construction hereinbefore described it will be observed that the treating chamber 6 measures considerably more in dimensions 10 vertically than horizontally, and said treating chamber preferably flares somewhat toward its lower extremity and has a height of about eighteen feet and a mean diameter of about three feet.

15 20 indicates a body of coal supplied to the treating chamber 6 and consisting of lumps or pieces and as filling said chamber about three quarters full. The treating chamber 6 is therefore shown as containing 20 a substantially vertical column of hydro-carbon-containing solid or non-liquid carbonaceous material convertible by suitable caloric treatment into gases, coke and by-products.

25 A pipe 21, employed in conducting vapors and gases from the treating chamber 6, communicates with said chamber at one side of the upper end portion of the chamber and at a point spaced upwardly from 30 the body of coal 20 and forms the fluid-outlet of said chamber. The pipe 21 is arranged, in the main, externally of the retort and discharges into the fluid-receiving upper end 35 of the upright worm 22 of a condenser shown arranged at one side of and spaced from the retort. Said condenser comprises a tank 23 containing said worm and kept supplied with cold water 25 in any approved manner, and the lower end of said worm forms the outlet of the condenser for the liquid or condensate resulting from condensation of vapors in said worm and discharges into the upper portion of a receiver or condensate-collecting chamber 26 which 40 is therefore arranged to receive the condensate and accompanying uncondensed gases from the condenser. A drain-pipe 27 is arranged to drain condensate from the condensate-collecting chamber 26 and has a 45 normally closed valve 28.

50 The condensate-collecting chamber 26 communicates, at its top or upper portion, with a short pipe 30 extending upwardly from said chamber and connected, at its upper end, with the lower end of and communicating with a substantially vertical tubular metal shell 31 forming a support for a water-conducting pipe 32 which extends into the chamber formed internally of 55 said shell and is provided, internally of said shell, with a sprayer 33. The water-conducting pipe 32 has a normally closed valve 35 externally of the shell 31, and said shell is provided internally, between the sprayer 33 and the pipe 30, with a plurality of ver-

tically spaced substantially horizontal baffle-members 36 relatively arranged as required to retard the movement of fluid internally and endwise of said shell. The shell 31 is connected, at its upper end, to and communicates with a short pipe 37 communicating with a T 38 formed on one end of a sectional pipe 39 arranged above the condenser and above and externally of the treating chamber 6, and said sectional pipe 75 has a considerable portion thereof surrounding and extending longitudinally of and considerably larger transversely than the pipe 21. The joints between the pipes 21 and 39, where the pipe 21 extends through 80 portions of the pipe 39, are rendered fluid-tight in any approved manner. The sectional pipe 39 discharges into the fluid-inlet 40 of a gas-pump 41 operated in any approved manner.

85 The fluid-outlet 42 of the pump 41 discharges into an upright sinuous pipe 43 at the upper end of the pipe, and said pipe is arranged internally of the combustion-chamber 45 of a heating furnace 46 arranged at one side of and near the retort. The sinuous pipe 43 discharges, at its lower end, into a pipe 47 extending from within the combustion-chamber 45 to the lower end portion of the retort and forming the fluid-inlet of the treating chamber 6. The walls of the combustion-chamber 45 are composed of highly refractory material, such, for instance, as carborundum, and said chamber has an outlet 48 at its upper end for products of combustion. Within the lower portion of the combustion-chamber 45 is a heating burner 50 supplied with an inflammable aeriform mixture or fuel by a pipe 51 having a valve 52 externally of said 105 chamber.

110 Each of opposite side walls of the combustion-chamber 45 is provided, at each of different heights between the upper end and lower end of the sinuous pipe 43, with a pair of substantially horizontal spaced baffle-plates 53 extending toward and spaced from the other of said walls, and the pairs of baffle-plates of each of said walls are staggered in relation to and spaced from the 115 pairs of baffle-plates of the other of said walls. The sinuous pipe 43 winds within the combustion-chamber 45 in such a manner, in relation to the baffle-plates 53, as to extend between adjacent pairs of baffle-120 plates 53 of each of opposite baffle-plate-supporting walls of said chamber.

125 The pump 41 is employed in forcing gases or fluid into the sinuous pipe 43 from the sectional pipe 39, and the last-mentioned pipe is provided, between said pump and the pipe 21, with a valve 55.

56 indicates a pipe for supplying steam, and said pipe has two branches 57 and 58 having normally closed valves 59 and 60 re- 130

spectively and communicating the one with the fluid-outlet 42 of the pump 41 and the other with the pipe 47 at a point between the heating furnace and the retort, and said pipe 47 is provided, between the branch-pipe 58 and the retort, with a pyrometer 61.

The T 38 is in communication with a pipe 62 adapted to be employed in conducting gas to a gas-holder not shown. The gas-conducting pipe 62 has a valve 63 for interrupting communication, when desired, through said pipe, and said pipe is provided, between said valve and the T 38, with a diagrammatically illustrated check-valve 65 for preventing reflux of gas from said pipe into said T.

Joints between component parts of the hereinbefore described apparatus are not only rendered fluid-tight wherever required but formed in such a manner as to withstand heat and strains to which said parts may be subjected. Means for forming and sealing such joints are too well known to require description and illustration in this specification. Also, in making said component parts such metal or material, as will withstand the heat and wear and tear to which said parts may be subjected, is employed.

For treating coal by my improved process the operation of the hereinbefore described apparatus is as follows:

The bottom door 10 of the retort is closed, if not already closed, and the top door 9 is opened, if not already open, to permit the feeding of coal at the last-mentioned door into the treating chamber 6, and enough coal is supplied to said chamber to fill said chamber about three-quarters full or to within such a distance of the upper extremity of said chamber as to leave space enough, over the body of coal supplied to said chamber, for upward expansion of said body of coal during caloric treating of the coal. The valves 55 and 63 are opened, if not already open, and the furnace 46 is operated in such a manner that the sinuous pipe 43, and gases or fluid passing internally of and endwise through said pipe, are heated to and kept heated, as long as desired, at an adequately high temperature such, for instance, as a temperature of from one thousand to three thousand degrees Fahrenheit. It will be observed, therefore, that the sinuous pipe 43 forms an externally heated hollow heating coil for heating gases or fluid passing internally and endwise of and through said coil. The pipe 21 and the condenser-worm 22 form a passageway leading from the space next above the column or body of coal 20 in the treating chamber 6 to the upper portion of the condensate-collecting chamber 26. The pipe 30, the sprayer-containing tubular member 31, the pipe 37 and the sectional pipe 39 form a passageway leading from said por-

tion of said condensate-collecting chamber to the inlet 40 of the pump 41, and the pipe 62 forms a gas-outlet for said passageway and is employed in conducting illuminating gas or water-gas, as the case may be, to a gas-holder not shown. The outlet 42 of the pump 41, the heating coil 43 and the pipe 47 form a passageway leading to the lower portion of the treating chamber 6 and discharging directly into the lower end portion of the column or body of coal 20.

Obviously air and gaseous fluid are contained in said passageways and in the treating chamber 6 and in the interstices of the body of coal 20, and the pump 41 is operated not only as required to create the desired suction in the pipe or fluid-outlet 21 of said chamber and so as to cause gases and vapors to pass at said fluid-outlet from said chamber to the condenser-worm 22 and thence through the upper portion of the condensate-collecting chamber 26 into and through the passageway comprising the pipe 30, tubular member 31 and sectional pipe 39 into the inlet 40 of the pump, but to force the desired volume of gases or fluid from the pipe 39 into and through the passageway comprising the heating coil 43 and the pipe 47 and into the lower portion of the treating chamber 6 and consequently into the lower end portion of and upwardly through the column or body of coal 20.

It will be observed, therefore, that the gases or fluid heated by and internally of the heating coil 43 form a gaseous heating agent having an adequately high temperature such, for instance, as a temperature of from one thousand to three thousand degrees Fahrenheit, that the column or body of coal or material in the treating chamber 6 is calorically treated by the penetration thereof and the passage therethrough of said gaseous heating agent, that vapors and gases are evolved from said body of material during the caloric treatment of said material by said heating agent, that during the required operation of the pump 41 gases and vapors are drawn from the treating chamber at the fluid-outlet of said chamber into the condenser-worm 22 and therein subjected to a condensing temperature, that the condensate formed in said condenser-worm is passed into the condensate-collecting chamber 26, that also gases received by said condenser-worm from the aforesaid treating chamber and remaining uncondensed upon their subjection to the aforesaid condensing temperature pass into the condensate-collecting chamber, that during the operation of the pump 41 uncondensed gases are drawn from the condensate-collecting chamber 26 through the gas-outlet 30 of said chamber into the sprayer-containing tubular shell 31 and are washed by the operation of the sprayer 33 in any approved manner, that the washed gases are drawn

from within said shell into the sectional pipe 39 wherein said gases are preheated by the pipe 21 heated by the hot vapors and gases passing from the treating chamber to the 5 condenser, that obviously the hot gases and vapors passing from the treating chamber to said condenser are somewhat cooled by the comparatively cold gases passing externally 10 of the pipe 21 through the sectional pipe 39, and that the last-mentioned gases, being preheated during their passage through said sectional pipe, are drawn from within said sectional pipe by and during the aforesaid operation of the pump 41 and forced into and 15 through the heating coil 43 and pipe 47 into the body of material being calorically treated in the treating chamber.

In treating a column or body of coal in the treating chamber 6 to produce illuminating gas, steam is not, of course, admitted to the said chamber, and in practising said process for the production of illuminating gas, coke or water-gas the condensate passing from the condenser into the condensate-collecting chamber 26 will be found to consist, in the main, of oils, tarry matter and water, and water also passes into said condensate-collecting chamber from the sprayer 33, and liquid or matter is periodically drained from said condensate-collecting chamber through the drain-pipe 27.

In the destructive distillation of solid bituminous material by the operation of my improved apparatus obviously pressure 35 will be developed in the passageway comprising the pipe 30, tubular shell 31, pipe 37 and sectional pipe 39 by the accumulation, in said passageway during the operation of the pump 41, of gases which have been 40 evolved from the body of carbonaceous material being calorically treated in the treating chamber 6 and not condensed in their passage through the condenser, and obviously the check-valve 65, when gases have 45 accumulated in said passageway to such an extent as to develop in said passageway a pressure high enough to unseat or open said valve, will be unseated by said pressure, and obviously, as soon as said valve opens, gas is 50 permitted to pass from said passageway through the gas-conducting pipe 62 adapted to be employed, as hereinbefore indicated, in conducting gas to a gas-holder not shown, and of course said valve, upon opening, will 55 remain open as long as the required pressure is being maintained in said passageway and as long as the pressure between said valve and said gas-holder is less than the check-valve-opening pressure in said passageway.

60 In producing illuminating gas, coke or water-gas from coal or similar carbonaceous material, the body of coal or carbonaceous material in the treating chamber 6 is treated by the continuous passage, into said body of material, of a gaseous heating agent having

an adequately high temperature such, for instance, as a temperature of from one thousand to three thousand degrees Fahrenheit, until substantially all volatile matter to be evolved from said body of carbonaceous material has been evolved and driven from said material and out of the treating chamber. 70

When a fine grade of blue water gas is to be produced from the coke or carbonaceous residue resulting from the treatment of coal 75 or similar carbonaceous material in the treating chamber 6, steam is admitted, by opening the valve 59, from the steam-supplying pipe 56 through the branch-pipe 57 to the heating coil 43 and highly superheated 80 in said coil and passed with hot gases from within said coil into the body of incandescent, carbonaceous material in the treating chamber. When in making water-gas the temperature in the treating chamber 85 rises above the desired point the speed of operation of the pump 41 is reduced and the valve 59 is closed and the valve 60 opened so as to admit steam from the steam-supplying pipe 56 through the branch-pipe 58 and 90 pipe 47 into the incandescent body of coke in the treating chamber.

When, in the treatment of coal or similar carbonaceous material, coke is the main product desired the body of carbonaceous material in the retort is subjected to the hereinbefore described caloric treatment until substantially all volatile matter has been removed or separated from said body of carbonaceous material and passed out of the 95 retort, whereupon the operation of the pump 41 is interrupted and the valve 55 is closed and steam is admitted through the pipes 58 and 47 to the body of incandescent coke, and blue water-gas is made until the temperature 100 of the body of coke has been lowered to a point at which the blue gas still produced is no longer of a desirable quality, and thereupon the body of coke is permitted to cool until the temperature of the body of coke 105 has fallen below an ignition temperature when exposed to air, whereupon the coke is discharged from the retort upon opening the bottom door 10. The discharged coke will be found to have a high B.t.u. value and 110 to be of a quality suitable for the finest metallurgical processes.

Of no considerable importance during the operation of the herein-described apparatus is the passing of the uncondensed vapors and 115 gases from the condenser 23 into the condensate-receiving chamber 26, and the passing of the uncondensed gases from said chamber upwardly into the passageway formed by the pipe 30, shell 31 and pipes 37 120 and 39, so as to insure the ascent of all gases received by said chamber into said passageway. Of vast importance, to minimize the waste of heat from the hot vapors and gases 125 passing from the treating chamber 6 of the 130

retort through the pipe 21 to the condenser 23, is the passing, externally of and next along said pipe, of a portion of the gases which have remained uncondensed during the subjection, to a condensing temperature in said condenser, of hot gases and vapors which have passed from the retort through said pipe. Also, during the operation of my improved apparatus occurs the passage of some gases which have remained uncondensed during their subjection to said condensing temperature to a point adjacent the upper end portion of the retort and thence to the lower end portion of the retort, and it will be observed that said gases, while feeding them to said lower end portion of the retort, are subjected to the temperature required to produce the desired gaseous heating agent for calorically treating the body of material in the retort, and it will also be observed that by the hereinbefore described relative arrangement of the pipes 21 and 39 occurs the transmission of heat from hot vapors and gases in the pipe 21 to the uncondensed gases passing through the pipe 39.

What I claim is:—

1. Apparatus for the destructive distillation of solid bituminous materials, comprising a retort having a treating chamber in which a body of said material is to be confined, a condenser, a pipe discharging at one end portion thereof into the condenser and communicating at its other end portion with the aforesaid chamber and arranged to conduct vapors and gases to the condenser from one end portion of said chamber and also arranged externally of said chamber and condenser between said end portions of the pipe, a condensate-receiving chamber arranged to receive condensate and accompanying uncondensed gases from the condenser, a passageway communicating with and at the upper portion of said condensate-receiving chamber and extending to and around and endwise of the aforesaid pipe, means whereby gases may be washed in said passageway between said pipe and the condensate-receiving chamber, a passageway discharging at the opposite end portion of and into the aforesaid treating chamber, means whereby gases may be forced into the second-mentioned passageway from the first-mentioned passageway, and means whereby gases conducted by the second-mentioned passageway may be heated to produce a gaseous heating agent.

2. Apparatus for the destructive distillation of solid bituminous materials, comprising

ing a retort having a treating chamber in which a body of said material is to be confined, a condenser, a pipe discharging at one end portion thereof into the condenser and communicating at its other end portion with the aforesaid chamber and arranged to conduct vapors and gases to the condenser from one end portion of said chamber, and also arranged externally of said chamber and condenser between said end portions of the pipe a condensate-receiving chamber arranged to receive the condensate and accompanying uncondensed gases from the condenser, a passageway communicating with and at the upper portion of said condensate-receiving chamber and extending to and around and endwise of the aforesaid pipe and to the second-mentioned end portion of the pipe, a passageway discharging at the opposite end portion of and into the aforesaid treating chamber, means whereby gases may be forced into the second-mentioned passageway from the first-mentioned passageway, and means whereby gases being conducted by the second-mentioned passageway may be heated to the temperature required to produce the desired gaseous heating agent.

3. Apparatus for the destructive distillation of solid bituminous materials, comprising a retort having a treating chamber in which a body of said material is to be confined, a condenser, a pipe communicating at one end portion of and with said chamber and discharging into the condenser, and arranged externally of said chamber and condenser between its end portions a passageway extending around and endwise of said pipe and adapted to receive gases subjected to and remaining uncondensed at the condensing temperature in the condenser, a passageway discharging at the opposite end portion of and into the aforesaid chamber, means whereby gases preheated in the first-mentioned passageway by heat transmitted from hot vapors and gases conducted by the aforesaid pipe may be forced from said first-mentioned passageway into the second-mentioned passageway, and means whereby gases being conducted by said second-mentioned passageway may be heated to the temperature required to produce the desired gaseous heating agent.

In testimony whereof I sign the foregoing specification this 18th day of December, 1922.

ARTHUR M. SMITH.
